(57) **CLAIM**

The ornamental design for a tool box, as shown and described.

DESCRIPTION

FIG. 1 is a top, front and right side perspective view of a tool box in accordance with my new design;

FIG. 2 is a bottom, front left side perspective view of the tool box in accordance with my new design;

FIG. 3 is a front elevational view of the tool box in accordance with my new design;

FIG. 4 is a rear elevational view of the tool box in accordance with my new design;

FIG. 5 is a top plan view of the tool box in accordance with my new design;

FIG. 6 is a bottom plan view of the tool box in accordance with my new design;

FIG. 7 is a right side elevational view of the tool box in accordance with my new design; and,

FIG. 8 is a left side elevational view of the tool box in accordance with my new design.

The broken line showing of environment in FIGS. 1-4, 7 and 8 is for illustrative purposes only and forms no part of the claimed design.

In FIGS. 1-4, 7 and 8, the tool box is shown broken away by a break line to illustrate an indeterminate height of the tool box. The precise height of the tool box is not being claimed.
